UNITED STATES PATENT OFFICE.

SILAS BECKEY, OF CASCADE, MICHIGAN.

PORTABLE FENCE.

SPECIFICATION forming part of Letters Patent No. 286,522, dated October 9, 1883.

Application filed September 14, 1883. (No model.)

To all whom it may concern:

Be it known that I, SILAS BECKEY, a citizen of the United States, residing at Cascade, in the county of Kent, State of Michigan, have 5 invented a new and useful Improvement in Portable Fences, of which the following is a specification.

My invention relates to an improved portable fence; and it consists in the peculiar construction of the posts for securing the panels in position, and in an improved corner-post, substantially as hereinafter described, and specifically pointed out in the claims.

In the drawings, Figure 1 is a perspective view of my improved portable fence. Fig. 2 is a view of the post; Fig. 3, a view of the improved corner-post. Figs. 4 and 5 are views of my improved corner-connection.

A in the figures shows the panel, which may 20 be of boards, of wire, of rails, or of pickets, or may be combined of any or all of these, or of lattice, rustic patterns, or any other of the usual forms of panel construction. When cross-bars are used, it is better to fasten the bar 25 on one end upon the opposite side from that at the other, to allow the flat sides of the panels to lie together smoothly and firmly in the posts, the cross-bars falling on the outside and binding firmly on the uprights.

B is the bed-piece of the post or clamp, and 30 serves as the block to raise the fence from the ground and to hold it in position.

C C' are the uprights; b, the hinge-bolts; c, the loop. d and d' are the braces.

The bed-piece should be of sufficient length 35 and weight to hold the fence firmly and afford strength for the attachment of the uprights. The uprights should reach the top of the uppermost rail, and higher, if desired. Both 40 are fastened to the bed-piece by bolts at such a distance apart as to fit snugly to the panels when in position, so that they may firmly clamp them, and they should both turn on the bolts as hinges, so as to fall away when released from the loop.

Upright C is provided with a series of notches, g, with any one of which the looped 45 end of brace d may be engaged, and the bed-piece is also notched on its under side at g', to facilitate the adjustment of brace d', the looped

end of which may be engaged therewith in a similar manner. By this construction the fence can be set up on sideling or hilly grounds, as the uprights, being pivoted, can be readily forced to the position required, and the braces 55 can be easily adjusted when desired.

The loop c, made of wire of any convenient size, passes through one upright at sufficient distance from the top to pass under the upper rail of the panel, or through any desired aperture in the same, and is made long enough to reach and drop over the end of the other upright, which may be beveled or chamfered to receive it. The loop sliding downward upon this upright holds it firmly to its place against 60 the inserted panels, and thus binds them solidly together. Another and more convenient method is to make a free loop of sufficient length to pass entirely around both pivoted uprights, through the panels, and when placed 65 around one, with the first panel already in place, the other panel is inserted, its end raised to receive the loop, the remaining upright is brought up, when both loop and panel drop to position, making a firm and sure connection. Whatever be the construction of 70 the panels, the same method of uniting them will be substantially followed.

By using the double post or clamp formed by setting a hinged upright, C'', on each side 75 of a stationary standard, as shown by Fig. 3, each upright holding the extremity of a single panel, any desired angle may be turned, and a tract of any shape or contour may be inclosed.

It will be at once apparent that this fence may be removed from place to place or entirely, panel by panel, with perfect ease and celerity; or sections of several panels may be removed together for short distances, giving 90 great utility to this mode of construction, with corresponding economy in labor and material.

Having thus described its construction and use, what I claim as my invention, and desire to 95 secure by Letters Patent of the United States, is—

1. A corner-post consisting of a bed-piece, B, stationary standard D', double uprights C'' C', the hinge-bolts b b, and loops c c, combined 100

with panels A A, to form an angle or corner, substantially as shown.

2. In a portable fence, the improved post or clamp comprising bed-piece B, notched on its under side, uprights C C', pivoted thereto, upright C being notched at *g*, braces *d d'*, and loop *c*, substantially as set forth.

In testimony whereof I have hereunto set my hand this 10th day of September, 1883.

SILAS BECKEY.
